UNITED STATES PATENT OFFICE.

JOHN C. NICHOLLS, OF BLUE MOUND, ILLINOIS.

HEATER FOR BROODERS.

No. 814,171.

Specification of Letters Patent.

Patented March 2, 1909.

Application filed March 5, 1908. Serial No. 418,314.

To all whom it may concern:

Be it known that I, JOHN C. NICHOLLS, a citizen of the United States, and a resident of Blue Mound, in the county of Macon and State of Illinois, have invented a new and Improved Heater for Brooders, of which the following is a full, clear, and exact description.

The invention relates to poultry culture, and its object is to provide a new and improved heater for brooders, arranged to produce a proper heating of the air supplied to the young, to cause moistening of the heated air, and to allow convenient removal of the heater from the brooder, whenever it is desired to do so, for cleaning, repairing or other purposes.

The invention consists of novel features and parts and combinations of the same, which will be more fully described hereinafter and then pointed out in the claims.

A practical embodiment of the invention is represented in the accompanying drawings, forming a part of this specification, in which similar characters of reference indicate corresponding parts in both views.

Figure 1 is a sectional side elevation of the improvement, and Fig. 2 is a plan view of the same, showing the brooder in section.

The brooder A in the form of a suitable box is provided a distance above its bottom with a hover board B, from the sides of which depend aprons C of cloth or other suitable fabric, to permit the young to readily pass under the hover board B to the top thereof. The bottom of the brooder A is provided at or near its middle with an opening for the reception of the lower end D' of a rim D, extending a suitable distance up into the brooder and provided with an annular retaining flange D² resting on the upper surface of the bottom of the brooder A. Centrally into the rim D extends a burner E, of any approved construction, and onto the rim D fits or telescopes a heating drum F provided at its sides with upwardly and outwardly extending tubes F' leading to a heat-distributing chamber G, preferably made ring-shape and provided at the front and rear with outlet pipes H, extending first upwardly through the hover board B and then transversely, to connect with telescoping tubes H' attached to the front and rear of the brooder A and leading to the outside thereof, so as to conduct the smoke and gases from the distributing cham-

ber G by way of the pipes H, H', to the outside of the brooder A.

On top of the heating drum F is arranged a fresh air heating chamber I, into the side of which opens a pipe I' telescoping on a pipe I² attached to one side of the brooder A, and leading to the outside thereof, so that fresh air from the outside of the brooder can pass by way of the pipes I², I', into the air-heating chamber I, to be heated therein by the heat from the heating drum F. The outer end of the pipe I² is preferably protected by a suitable hood I³, to prevent dust and the like from passing with the air into the air-heating chamber I.

On top of the air-heating chamber I is set a moisture pan J for containing water, and provided with a removable top J' having its central opening J² for the escape of the moisture or vapor produced by evaporating the water contained in the pan J, and which water is heated by the heat of the heated air in the chamber I. The bottom of the pan J is provided with an upwardly-extending tube J³, forming an outlet for the air-heating chamber I and extending through the outlet opening J², from the side wall of which it is spaced to allow the escape of moisture or vapor close to the escape of the heated air from the chamber I. As illustrated in the drawings the heat-distributing chamber G surrounds the moisture pan J but is spaced from the same to allow proper circulation of the air in the brooder A below the hover board B. It will also be noticed by reference to Fig. 1 that the tops of the heat-distributing chamber G and the pan J are a distance below the hover board B, so that the moistened air passes into the brooder A immediately below the hover board B, from which the air is distributed to the space surrounding the heater and inclosed by the aprons C, which latter terminate a distance from the bottom of the brooder A, to allow heated air to rise in the brooder outside of the aprons C and the hover board B.

By the arrangement described the heater proper can be readily removed from the rim D whenever it is desired to clean or repair the heater, and by having the cover J' removable, the pan J can be readily filled with water whenever necessary. By the use of the telescoping pipes H, H' and I², I', the heater can be readily fitted to brooders of different sizes. It will also be seen that by

the arrangement described, the products of combustion from the burner E are utilized to the fullest advantage and are conducted to the outside of the brooder without danger of mingling with the heated air inside of the brooder; and by extending the tubes H up through the hover board B, the air above the hover board B is heated, that is, heated air is had above the heads of the young where it is most needed.

Having thus described my invention, I claim as new and desire to secure by Letters Patent:

1. A heater for brooders, comprising a heating drum, an air heating chamber 15 mounted on the said heating drum, and provided with an inlet extending to the outside of the brooder, a moisture pan for containing water mounted on top of the said air-heating chamber and provided with a cover having a central outlet for the moisture, the said air-heating chamber having a central outlet extending through the moisture pan and the cover outlet.
2. A heater for brooders, comprising a heating drum, an air heating chamber 25 mounted on the said heating drum, and provided with an inlet extending to the outside of the brooder, a moisture pan for containing water mounted on top of the said air-heating chamber, and provided with a cover having a central outlet for the moisture, the said air-heating chamber having an outlet extending through the cover outlet, an annular 30 heat-distributing chamber having an outlet extending to the outside of the brooder, and a connection between the said heating drum and the said heat-distributing chamber.
3. A heater for brooders, comprising a heating drum, an air-heating chamber 40 mounted on the said heating drum and provided with an inlet extending to the outside of the brooder, a moisture pan for containing water mounted on top of the said air-heating chamber and provided with a cover having a central outlet for the moisture, the said air-heating chamber having an outlet extending through the cover outlet, an annular 45 heat-distributing chamber having an outlet extending to the outside of the brooder, and a connection between the said heating drum and the said heat-distributing chamber.
4. A heater for brooders, comprising a heating drum, an air-heating chamber 50 mounted on the said heating drum, and provided with an inlet extending to the outside of the brooder, a moisture pan for containing water mounted on top of the said air-heating chamber, the latter surrounding the said water pan.
5. A heater for brooders, comprising a heating drum, an air-heating chamber 55 mounted on the said heating drum, and provided with an inlet extending to the outside of the brooder, a moisture pan for containing

water mounted on top of the said air-heating chamber and provided with a cover having a central outlet for the moisture, the said air-heating chamber having an outlet extending through the cover outlet, an annular distributing chamber having an outlet 60 extending to the outside of the brooder, and a connection between the said heating drum and the said heat-distributing chamber, the latter surrounding the said water pan and being spaced from the same.

5. The combination with a brooder, of a heating drum in the brooder, an air-heating chamber on top of the heating drum and having an inlet for fresh air and an outlet opening into the brooder, an annular heat 75 distributing chamber connected with the heating drum and having an outlet leading to the outside of the brooder, and a moisture pan for containing water mounted on top of the air heating chamber, the said moisture 80 pan being surrounded by the heat distributing chamber.

6. The combination with a brooder, of a heater comprising a heating drum removably held on the bottom of the said brooder, an air heating chamber on top of the said drum and provided with an inlet for fresh air, a moisture pan for containing water mounted on top of the air heating chamber, the said pan and air heating chamber having outlets 90 opening within the brooder, and an annular heat-distributing chamber surrounding the said moisture pan and communicating with the heating drum, the said annular chamber being provided with outlets extending to the outside of the brooder.

7. The combination with a brooder, of a heater comprising a heating drum removably held on the bottom of the said brooder, an air heating chamber on top of the said drum 100 and provided with an inlet pipe for fresh air formed in telescoping sections, a moisture pan for containing water mounted on said air heating chamber, the said moisture pan and air heating chamber communicating 105 with the interior of the brooder, and a heat distributing chamber having inlet pipes leading from the heating drum, and outlet pipes formed in telescoping sections and leading to the outside of the brooder.

In testimony whereof I have signed my name to this specification in the presence of two subscribing witnesses.

JOHN C. NICHOLLS.
